BOTTLE DRIER

Bruce G. Copping, Toronto, Ontario, Canada, assignor to The Coca-Cola Company, Wilmington, Del., a corporation of Delaware

Application December 20, 1938, Serial No. 246,829
In Canada September 22, 1938

10 Claims. (Cl. 34—95)

This invention relates to the beverage industry, and more particularly to a new and improved bottle wiper, having as its purpose the removing of moisture from the exterior of bottles.

It is generally recognized that the potability of most beverages is greatly enhanced by refrigeration; and this being so, it is customary to place such in what are commonly called "coolers," said devices broadly constituting nothing more than ice boxes in which bottles may be placed together with a quantity of ice, and water; the temperature of the contents of the bottles after a sufficient period of time then approximating that at which said water is maintained by its cooling factor.

This commonly used method of wet cooling has one serious drawback in that a bottle when removed from a cooler is obviously covered to a greater or less degree with moisture, which tends to drip upon the floor of the establishment in which the beverage is sold, often creating unsightly puddles and stains; and again, the hands of the purchaser immediately become wet through contact with the container, this being disagreeable, particularly to females. Further, said excess water may drip upon the clothes of the consumer, this action not being conducive to the promotion of good will, and it may also be noted that when the bottle is tilted at the conventional angle for drinking, said water tends to flow along the neck of the container and into the mouth of the consumer of the beverage, which is undesirable, particularly if the interior of the cooler has not been thoroughly cleaned, or the exterior of the bottle exposed to contamination.

Heretofore, several means have been suggested to take care of this undesirable feature, but these have been for the most part crude, and not particularly sanitary, as for example hanging a common towel adjacent the cooler in order that each purchaser may dry his bottle when such is removed from the water, this obviously becoming a public towel in a short time as the hands of successive persons come in contact therewith.

Other expedients in the nature of coasters and paper coverings for bottles have likewise been suggested, but these are not regarded as entirely satisfactory, in view of the additional cost incidental to furnishing such, incomplete and insufficient drying action, and a tendency of consumers not to go to the trouble of adjusting them in place, many purchasers apparently preferring to take the consequences of a wet bottle rather than be bothered with an accessory device.

An object of the instant invention is to provide

a wiper for removing water from the exterior of bottles.

A further object is to provide automatic action in such a device.

5 A still further object is to provide simplicity of construction and operation.

A still further object is to provide cheapness of construction in a bottle wiper.

Another object is to provide a reservoir for catching and retaining excess water in a device of the instant type.

Another object is to provide a wiper which is attractive in appearance and susceptible to ready attachment to premises upon which beverages

15 are sold.

These and other objects made apparent throughout the further progress of this specification are accomplished by means of my wiper, a full and complete understanding of which is facilitated by reference to the drawings herein, in which:

Fig. 1 is a view in perspective showing my device in inoperative position, with a bottle resting therein.

25 Fig. 2 is a vertical sectional view of the structure illustrated in Fig. 1.

Fig. 3 is a horizontal sectional view taken substantially along line 3—3 of Fig. 2.

Fig. 4 is a view similar to Fig. 3, taken, however, along the line 4—4 of Fig. 2.

Fig. 5 is an exploded view of my wiper, showing the various parts thereof in disassembled position.

Fig. 6 is a vertical sectional view showing a bottle as it appears during the drying operation.

Fig. 7 is a horizontal cross sectional view taken along the line 7—7 of Fig. 6.

Referring now to the drawings, my invention comprises what may be a cylindrical casing 10, having a circular opening 11 in its top of a diameter slightly in excess of that of bottles contemplated to be used with the wiper. Spacedly mounted on the side wall of casing 10 are four right-angled brackets 12 (Fig. 3), which are provided with holes 13 at their tops and bottoms for the reception of the ends 14 of cranks 15, said cranks being passed through a plurality of H-shaped sponge holders 16 in such manner as to permit said elements 16 to move downwardly and inwardly towards the central vertical axis of casing 10 upon manipulation.

A series of sponges or other absorbent elements 17 are mounted in holders 16 in a suitable manner, as by cementing for example, the interior vertical faces 18 of said drying elements being

preferably convexly curved to accommodate the outer contour of a bottle.

Attention is now directed to the bottom sponge holder assembly of my wiper, same comprising a perforated plate 19 (Fig. 5) to which is united a sponge or other appropriate drying member 20. Perforated plate 19 is in turn attached to four cross pieces 21 which meet each other at right angles and extend outwardly beyond the edges of said plate, said pieces being provided at their outer ends with holes or openings 22 calculated to receive the ends 23 of connecting links 24, said links being passed through the lower ends of holding elements 16 in such manner that the bottom assembly is pivotally connected therewith.

The lower portion of casing 10 is provided with a spring holder 25 (Fig. 2), in which is loosely encased a spring 26, the upper surface of which bears against the bottom of the lower sponge holding assembly described heretofore, the relative positioning of the various parts being such that said spring normally holds the bottom assembly and associated side elements in an open position approximating that suggested by Figs. 1 and 2.

The bottom or reservoir portion of casing 10 consists of a tightly fitting cup-like element 27 contemplated to be held in place through means of slots 28 (Fig. 5) in the upper portion thereof, which engage pins 29 fixedly mounted on opposite sides of the casing.

A bracket such as 30 may be attached to casing 10 for the purpose of mounting the wiper upon a wall, counter, or other fixture, as by receiving a tongue-like member 31 fastened to such anchorage. Or the entire wiper may be incorporated within a cooler itself, the structure described herein being primarily by way of illustration, and it being apparent that any mechanism involving the essential drying features of the instant structure comes within the purview and scope of my invention.

The operation of the instant device, while perhaps adequately suggested by the foregoing description, may, for the purpose of clarifying any possible doubts, be described as follows:

A bottle 32 is withdrawn from a cooler and inserted with water dripping therefrom through the upper opening 11 of casing 10, said bottle then being pressed downwardly as by placing the hand on the top 33 thereof, this action causing the bottom of said container to compress sponge or other absorbent element 20, and with continuing pressure, to compress spring 26, this downward movement continuing until the ends of 21 rest adjacent the top of spring holder 25 (Fig. 6).

During the movement just described, connecting links 24 have caused the side holding elements 16, together with the absorbent members carried thereby, to move downwardly and inwardly, this action resulting in compression of elements 17 against the wet sides of bottle 32. Such compression serves to transfer the undesirable water to the sponge members, and at the same time force such water out of the sponges, whereupon it drains downwardly through perforated plate 19 and through the perforations of spring holding element 25, into container 27. Said container naturally accumulates water from time to time, and may be emptied by simply twisting slightly in a counterclockwise direction in order that slots 28 may become disengaged

from pins 29, a downward pull on the container then serving to free same from the casing.

As bottle 32 is removed from the wiper, spring 26 automatically returns the bottom sponge holding assembly to its normal position, and at the same time side sponges 17 are returned to their retracted position, this movement, in permitting all of said sponges to return to their full size, further serving to absorb and remove any remaining water from the sides and bottom of the bottle, which may now be taken from the wiper and its contents enjoyed without the undesirable features associated with a wet container, described heretofore.

It is obvious that the instant device is subject to additional refinement, both by way of styling and in the finish and decoration imparted thereto, attractive color combinations at once suggesting themselves to the commercial designer.

From the foregoing, it is apparent that I have disclosed a new and useful bottle wiper, which is simple, positive, and automatic in its action; capable of being economically constructed; attractive in appearance; and adapted to serve its contemplated function in a thoroughly efficient manner.

While I have herein described a preferred embodiment of my invention, various changes, alterations, reconstructions, additions, and rearrangements of parts and structure may be resorted to without departing from the scope of the appended claims, which are to be as broadly construed as my contribution to the art justifies.

I claim:

1. In a device of the character described, a cylindrical casing, a bottle admitting aperture in the top thereof, a series of supporting brackets spacedly mounted within said casing, a series of vertically extending sponge holders vertically disposed within said casing, a plurality of links pivotally mounting said holders to said supporting brackets, sponges anchored in said holders, a bottom plate adjacent the lower ends of said sponges, a sponge mounted on the top of said plate, springs means for maintaining said bottom element in position, and links pivotally joining said plate with said sponge holding elements, whereby upon downward movement of said bottom element, as when same is contacted by the base of a bottle, said side sponges move inwardly and downwardly, pressing against the outer walls of such bottle and removing excess moisture therefrom.

2. In a device of the character described, a casing, a bottle admitting aperture therein, a series of supporting brackets mounted within said casing, a series of sponge holders disposed within said casing, a plurality of links pivotally mounting said holders to said supporting brackets, sponges anchored in said holders, a bottom plate adjacent said sponges, a sponge mounted on the top of said plate, means for maintaining said bottom element in position, and links pivotally joining said plate with said sponge holding elements, whereby upon downward movement of said bottom element, as when same is contacted by the base of a bottle, said side sponges move inwardly and downwardly, pressing against the outer walls of such bottle and removing excess moisture therefrom.

3. In a device of the character described, a casing, a bottle admitting aperture therein, a series of supporting brackets mounted within said casing, a series of holders for water absorbent elements disposed within said casing, a

plurality of links pivotally joining said absorbent elements with said supporting brackets, water absorbent elements anchored in said holders, a bottom plate adjacent said water absorbent elements, a water absorbent element mounted on the top of said plate, means for maintaining said bottom element in position, and links pivotally joining said plate with said holders for water absorbent elements, whereby upon downward movement of said bottom element, as when same is contacted by the base of a bottle, said side water absorbent elements move inwardly and downwardly, pressing against the outer walls of such bottle and removing excess moisture therefrom.

4. In a device of the character described, a casing, a bottle admitting aperture therein, a series of supporting brackets mounted within said casing, a series of sponge holders disposed within said casing, a plurality of links pivotally joining said holders with said supporting brackets, sponges anchored in said holders, a bottom plate adjacent said sponges, a sponge mounted on the top of said plate, means for maintaining said bottom element in position, and links pivotally joining said plate with said sponge holding elements, whereby upon downward movement of said bottom element, as when same is contacted by the base of a bottle, said side sponges move inwardly and downwardly, pressing against the outer walls of such bottle and removing excess moisture therefrom, and a detachable container secured to the bottom of said cylinder for the purpose of collecting water thus removed.

5. In a device of the character described, a casing, a bottle admitting aperture therein, a supporting element affixed to the side of said casing, a series of supporting brackets mounted within said casing, a series of sponge holders disposed within said casing, a plurality of links pivotally joining said holders with said supporting brackets, sponges anchored in said holders, a bottom plate adjacent said sponges, a sponge mounted on the top of said plate, means for maintaining said bottom element in position, and links pivotally joining said plate with said sponge holding elements, whereby upon downward movement of said bottom element, as when same is contacted by the base of a bottle, said side sponges move inwardly and downwardly, pressing against the outer walls of such bottle and removing excess moisture therefrom.

6. In a device of the character described, a casing, a bottle admitting aperture therein, a series of supporting brackets mounted within said casing, a series of holders for moisture absorbing means disposed within said casing, a plurality of links pivotally joining said moisture absorbed means with said supporting brackets, moisture absorbing means anchored in said holders, a bottom plate adjacent said moisture absorbing means, a moisture absorbing means mounted on the top of said plate, means for maintaining said bottom element in position, and links pivotally joining said plate with said holders for moisture

absorbing means, whereby upon downward movement of said bottom element, as when same is contacted by the base of a bottle, said side moisture absorbing means move inwardly and downwardly, pressing against the outer walls of such bottle and removing excess moisture therefrom.

7. In a device of the character described, a casing, a bottle admitting aperture therein, a series of supporting brackets mounted within said casing, a series of sponge holders disposed within said casing, a plurality of links pivotally joining said holders with said supporting brackets, sponges anchored in said holders, a bottom plate adjacent said sponges, means for maintaining said bottom element in position, and links pivotally mounting said plate with said sponge holding elements, whereby upon downward movement of said bottom element, as when same is contacted by the base of a bottle, said side sponges move inwardly and downwardly, pressing against the outer walls of such bottle and removing excess moisture therefrom.

8. In a device of the character described, supporting means, a plurality of longitudinally extending moisture absorbent elements hingedly mounted to the interior thereof, and a moisture absorbent base pivotally joined to said absorbent elements, whereby upon pressure being exerted upon said base, said elements are drawn inwardly to contact the side walls of a container and remove excess water therefrom, and means for maintaining said absorbent elements in open position for receiving a container.

9. In a device of the character described, supporting means, moisture absorbent means disposed therein, means pivotally mounting said moisture absorbent means to the interior of said supporting means, and a bottom plate pivotally joined to said moisture absorbent means in such a manner that a downwardly exerted force on said plate will draw said absorbent means downwardly and inwardly.

10. In a device of the character described, a housing having an opening in one end through which an article to be dried can be inserted, moisture absorbing side pads in the housing, means in said housing for mounting said pads for movement toward and away from a line passing centrally through said opening and longitudinally through said housing with one end of each of the pads adjacent the opening and the other end of each of the pads remote therefrom, a moisture absorbing end pad, means for mounting said end pad near the ends of the side pads remote from said opening for movement parallel to said line and toward and away from said opening, connections between the means for mounting the side pads and end pad so constructed and arranged that when said end pad is moved away from the opening by pressure of an article to be dried the side pads are moved toward said line, and resilient means to move the end pad toward the opening and the side pads away from said line when the pressure of an article to be dried on said end pad is released.

BRUCE GRAY COPPING.
